CLAIM

The ornamental design for a cylindrical hanging chair, as shown and described.

DESCRIPTION

FIG. 1 is a front view of a cylindrical hanging chair showing a first embodiment of the new design.

FIG. 2 is a rear view of the cylindrical hanging chair of FIG. 1.

FIG. 3 is a left side view of the cylindrical hanging chair of FIG. 1.

FIG. 4 is a right side view of the cylindrical hanging chair of FIG. 1.

FIG. 5 is a top view of the cylindrical hanging chair of FIG. 1.

FIG. 6 is a bottom view of the cylindrical hanging chair of FIG. 1.

FIG. 7 is a front view of a cylindrical hanging chair showing a second embodiment of the new design.

FIG. 8 is a rear view of the cylindrical hanging chair of FIG. 7.

FIG. 9 is a left side view of the cylindrical hanging chair of FIG. 7.

FIG. 10 is a right side view of the cylindrical hanging chair of FIG. 7.

FIG. 11 is a top view of the cylindrical hanging chair of FIG. 7; and,

FIG. 12 is a bottom view of the cylindrical hanging chair of FIG. 7.

In the drawings, the ornamental design that is claimed is shown in solid lines. The broken lines in the drawings illustrate portions of the cylindrical hanging chair that form no part of the claimed design.
